UNITED STATES PATENT OFFICE.

EMIL GARDIE AND MARION HILL, OF SOUTH ST. PAUL, MINNESOTA.

SCREENING-MACHINE FOR SAND AND GRAVEL.

1,098,946.

Specification of Letters Patent. Patented June 2, 1914.

Application filed July 22, 1912. Serial No. 710,791.

To all whom it may concern:

Be it known that we, EMIL GARDIE and MARION HILL, citizens of the United States, residing at South St. Paul, in the county of 5 Dakota and State of Minnesota, have invented a new and useful Screening-Machine for Sands and Gravels, of which the following is a specification.

Our invention relates to screening machines for separating stones, gravels and sands in preparing materials for concrete, mortar, plastering &c. and the main object is to produce an improved efficient automatic machine for said purposes.

15 In the accompanying drawing,—Figure 1 is a top view of our complete machine. Fig. 2 is a longitudinal vertical section on the line *a—a* Fig. 1. Fig. 3 is a side elevation of the machine shown in Fig. 1 with 20 most of the sand and gravel supplying mechanism to the right and the guard rails of steps and platform omitted. Fig. 4 is an enlarged detail side view of one of the screen frames and screens therein. Fig. 5 25 is an enlarged end elevation of the screens and their frames suspended by links from the machine frame, the latter shown in section.

Referring to the drawings by reference 30 numerals, 1 designates the main frame of the machine and is provided with legs or supporting posts 2 which are of sufficient height to permit any kind of wagons, carts or cars (not shown) to pass underneath the bins 3, 35 which hold the screened materials in readiness for removal from the machine through outlets 4, which are normally closed by shutters 5 operated by handles 6 fixed in same.

As best shown in Fig. 2, the bins are 40 divided into four compartments or smaller bins, 3, 3^a, 3^b and 3^c for the reception of coarse gravel, fine gravel, coarse sand and fine sand respectively. Above said bins are suspended by links 7 and 8 two screen 45 frames 9 and 10, of which the upper one contains a very coarse screen 11 and a lower and finer screen 12; and the lower frame contains a still finer screen 13 and the finest screen 14. Each screen frame is formed of 50 two pairs of parallel angle-iron bars 15, to whose horizontal flanges the screens are fastened, while the vertical flanges form side guards to keep the materials on the screen.

Said side bars are secured together by trans- 55 verse bars 16 which also support the screens. In Fig. 5 is shown that said transverse bars

may be angle bars in the lower part of each frame and plain flat bars in the upper part of each frame, so as to leave more room for materials between the two screens in each 60 frame.

Each screen frame is held and agitated in a substantially horizontal position by a pair of eccentric rods 17 and 18 having straps 19 embracing eccentrics 20 and 21, which are 65 fixed on a shaft 22. The latter is journaled in bearings 24 on the frame (see Figs. 2 and 3) and carries a fixed pulley 23, which is driven by a belt 25 and a pulley 26 that is fixed on a shaft 27; the latter shaft has a 70 large pulley 28 driven by a belt 29 and an electric or other motor 30, which in Fig. 3 may be seen through an opening broken away in the wall and one of the doors 31 of a motor house 32, which is mounted on posts 75 33 and preferably connected with the frame 1 of the machine; the belt 29 runs through apertures in the roof of the motor house, and in the platform 46.

Fixed on the shaft 27 is a pinion 34 which, 80 preferably by means of an intermediate idler gear 34^a, drives a gear wheel 35, which is fixed on a shaft 36 having near its middle 85 fixed a roller 37. Said roller engages in the upper loop of an endless conveyer belt 38 whose lower loop passes over a roller 39. Both of said rollers are journaled in an inclined frame 40, supported on trestle work 41. In the frame 40 are also journaled a series of rollers 42, each of which has its 90 diameter reduced toward the middle so as to form a single annular groove, the function of which is to cause the upper flight of the endless conveyer belt to assume a grooved shape and in such groove carry the materials whose weight causes the groove. 95

In Figs. 1 and 2, 43 designates a supply of mixed sands, gravels and small stones to be fed to the machine for separation. In said views is also shown an inclined, and in the 100 middle upwardly bulged plate 44, which is secured at 45 to the main frame; the function of the said plate is to spread upon the upper screen the sand and gravel passing from the upper end of the conveyer onto the 105 screens, so that the conveyer belt may be much narrower than the screens and still the entire width of the screens will be in active use as soon as the materials are dropped upon them.

At the front side of the machine is arranged a platform 46 having an inclined ex-

tension 47, the latter with cleats 48. The entire platform and extensions may have guard rails 49 (shown in Fig. 1). From the main platform 46 extend steps 50 to a lower 5 and smaller platform 51 in front of the motor house, and from the small platform to the ground extend steps 52.

The operation of the machine is as follows: The machine is placed where the crude material 43 can easily be supplied to the conveyer 38. The motor is then started, and as the conveyer carries the crude material upon the spreader 44, the latter spreads it upon the end of the upper screen that extends in under the spreader. The eccentrics then by swinging the links 7 and 8 between a vertical and an inclined position (as shown in Figs. 2 and 3) causes the materials to move upon the screens in a direction away from the spreader 44; and as it is obvious that such motion of the screens throws the materials upward and forward, clogging, even if the materials are wet, is prevented, and the separating effect is increased as compared with a mere horizontal vibration of the screens. Said effect is further increased by the slight rocking movement of the screens, which results from a greater vertical throw of the eccentrics than of the pivots 30 in the lower ends of the links 7 and 8 which support the screens. When it is preferred to have the eccentric shaft turn in the opposite direction of the arrow *b* in Fig. 2 the motor is reversed, the pinion 34 and gear 35 are meshed directly and the intermediate idler gear 34¹ omitted. All rocks or stones that are too large to pass through the top screen pass over it and are guided out of the machine by a chute 53; the large gravel 40 passes from screen 12 along chute 54 into bin 3; the finer gravel passes from screen 13 over chute 55 into bin 3^a; the coarsest sand

passes from screen 14 and over chute 56 into bin 3^b, while the finest sand drops through screen 14 directly into bin 3^c; and if any of 45 it moves past the bin the chute 57 will guide it into the bin; but as a rule the fine sand is precipitated through all the screens before passing from over the bin 3^c.

As already stated, any of the screened materials may be loaded from its bin into the wagon, cart or car by placing the car or wagon underneath the bin and opening the bottom valve or shutter of the bin.

What we claim is:—

1. In a screening machine and mounted in a suitable frame, the combination of pivotally suspended links, a screen frame pivotally suspended in the links, and means arranged to move the screen frame from a vertical position of the links to one side therefrom only to the vertical position and back again.

2. In a screening machine and mounted in a suitable frame, the combination of a pair 65 of pivotally suspended hangers, a screen frame trunnioned in the lower ends of the hangers and provided with one or more screens, a shaft journaled on the frame, an eccentric fixed on the shaft, a yoke on the eccentric, and a rod rigidly secured with one end to the yoke and the other end to the screen frame; said hangers being so arranged relative to the eccentric that they swing between a vertical position and a position inclined from one side only of the vertical position.

In testimony whereof we affix our signatures, in presence of two witnesses.

EMIL GARDIE.
MARION HILL.
